UNITED STATES PATENT OFFICE.

WALTER CHARLES SCOTT, OF PLAINFIELD, NEW JERSEY, ASSIGNOR TO ISABELLA SCOTT AND DAVID J. SCOTT, EXECUTORS OF WALTER SCOTT, DECEASED, LATE OF PLAINFIELD, NEW JERSEY.

PLATE-PRINTING MACHINE.

1,206,929.

Specification of Letters Patent.

Patented Dec. 5, 1916.

Original application filed July 30, 1914, Serial No. 854,081. Divided and this application filed November 20, 1915. Serial No. 62,447.

To all whom it may concern:

Be it known that I, WALTER C. SCOTT, a citizen of the United States, and a resident of Plainfield, in the county of Union and 5 State of New Jersey, have invented certain new and useful Improvements in Plate-Printing Machines, of which the following is a specification.

The present invention relates to printing machines, and more particularly to machines employing flexible printing plates such as planographic machines or lithographic presses printing from a zinc, aluminum or other plate or sheet held on the cylinder under tension, as well as intaglio machines and "offset" presses.

This application is a division of one filed July 30, 1914, Ser. No. 854,081.

In the usual rotary lithographic presses, 20 the form or design is carried on a zinc or aluminum plate, which is stretched over the surface of the plate cylinder by clamps holding and tightening the plates from each end, and the plate is always the full width 25 of the cylinder, irrespective of the size of the design, in order to allow the dampening and inking mechanisms to properly perform their functions. This is found very satisfactory and successful for the ordinary 30 lithographic work, in which sheets are printed and where the design is put on plates and the time consumed in preparing the plates is not a serious object. But in adapting this type of press and this style of 35 printing to periodical production, particularly where only one page, or a series of pages, can be gotten ready at a time, and where the news features compel the rapid production and quick change and clamping 40 of the plates, the ordinary style of cylinder is not suitable.

The main object of the invention is to adapt a planographic or like machine to newspaper and magazine work.

Another object of the invention is to provide clamping means of small dimensions and of sufficient capacity between circumferentially adjacent page forms.

One feature of the invention resides in 50 having a flexible form, on the form carrying cylinder, provided with side by side printing portions and intervening marginal

portions, together with means for supplying ink to the printing portions only, and means for dampening both the printing and 55 intervening marginal portions of the form, whereby smutting of the marginal portions is avoided. Preferably the form consists of side by side plates or printing surfaces removably secured to the cylinder and each 60 having a printing portion and a marginal portion.

The inking device, as here disclosed, preferably consists of an inking roller having a plurality of inking surfaces, or an interrupted inking surface, registering with the 65 printing portions of the form.

The dampening means preferably take the form of full length or uninterrupted dampening rollers engaging both the printing 70 and marginal portions of the form.

Other features of construction, combination of parts and arrangement of elements will appear as the specification proceeds.

In the accompanying drawings the invention 75 is disclosed in a concrete and preferred form, but changes of construction may be made without departing from the legitimate and intended scope of the invention as expressed in the appended claims. 80

In the said drawings: Figure 1 illustrates a diagrammatic side elevation of a machine embodying the invention. Fig. 2 is a sectional view substantially on the line 3—2 through the form cylinder showing a dampening roller in position. Fig. 3 is a sectional view also substantially on the line 3—2 showing an inking roller in position. Figs. 4 and 5 show details of construction 85 of the inking roller.

Similar characters of reference indicate corresponding parts in the several views.

20 is the impression cylinder, 1 the form carrying cylinder, while 9 are the dampening rollers and 10 the inking rollers. The 95 form carrying cylinder is grooved as at 2 which grooves are adapted to receive sliding dogs 21 which form spacing and clamping members for holding the jackets 3 in position, said dogs and jackets being formed 100 with beveled surfaces as shown for this purpose.

22 indicates screws for moving and clamping the dogs 21 in position.

- The jackets 3 are arranged in groups end to end, each group containing preferably a plurality of side by side jackets as shown. 4 indicates the printing plate or surface 5 stretched on each jacket and having the printing portion 23 and intervening marginal portions 24. Each jacket is provided preferably at both ends circumferentially with an undercut groove 25 forming overhanging end portions 26 which are closely adjacent in the different groups. Located in the grooves 25 are clamp bars 5 and 6 which are shaped to firmly hold the ends of the plate stretched over the outside of the jacket when secured together by means of the bolts 7. The plates are tightened and adjusted circumferentially on the jackets by means of the straining bolts 8 which draw the clamp bars 5 and 6 along the groove 25 of the jacket 3. It will be understood that the jackets are fitted with the printing plates before the jackets are placed on the cylinder, and that the bars 5 and 6 are fastened to the ends of the plates before the latter are placed on the jackets. This permits of having clamping bars and fastening devices of ample proportion within a small compass. It will further be noted that in this arrangement it is possible to have very narrow margins between the designs carried on the plates. In fact, these plate jackets can be made to almost butt the plates together. Also, by having extra jackets and clamp bars, changes in plates can be very readily made, as the plates can be clamped on these jackets and be ready to place on the cylinder in a very short time. This is of material advantage in case any page should by accident become injured. Also, it will be noted that each plate can be individually adjusted for register, if color printing is desired.
- 9 represents one of the water form rollers for dampening the plate. This roller is preferably full length or uninterrupted so as to dampen both the printing portions 23 and intervening marginal portions 24.
- 10 is an inking roller provided with an interrupted inking surface, or having a plurality of inking portions 27, as shown. In this way the marginal portions 24 of the plates are not smutted, while the entire form is dampened. This construction is necessary because it would not be possible to bevel the edges of the jackets lengthwise of the machine without correspondingly building up the dampening rollers—and that would interfere with the surface speed of the rollers and cylinders.
- In Fig. 4 is shown one way of recessing the inking roller. Here the stock 11 of the roller is turned to a smaller diameter opposite the marginal portions of the printing plates, and the usual packing 12 under the leather covering 13 is omitted, and the lat-

ter drawn to a smaller diameter by means of the wire wrapping 14.

In Fig. 5, the shaft 15 carries a plurality of rollers (only one shown) said rollers being each composed of a tube 16 covered with felt 17 and leather 18. The rollers are held on the shaft 15 by means of set screws 19.

What is claimed, is:

1. A printing machine comprising: a plurality of members constituting a printing couple, one of said members being a form carrying cylinder, a flexible form on said cylinder having side by side printing portions and intervening marginal portions, means for supplying ink to the printing portions only, and means for dampening both the printing portions and intervening marginal portions of the form. 75

2. A printing machine comprising: a plurality of members constituting a printing couple, one of said members being a form carrying cylinder, a flexible form on said cylinder consisting of side by side plates having printing portions with intervening 80 marginal portions, means for supplying ink to the printing portions only of the plates, and means for dampening both the printing portions and intervening marginal portions of the plates. 90

3. A printing machine comprising: a plurality of members constituting a printing couple, one of said members being a form carrying cylinder, a plurality of flexible plates, means for removably securing said 100 plates side by side on the form carrying cylinder, each plate having a printing portion and a marginal portion, means for supplying ink to the printing portions only, and means for dampening both the printing and 105 marginal portions. 95

4. A printing machine comprising: a plurality of members constituting a printing couple, one of said members being a form carrying cylinder, a flexible form on said cylinder having side by side printing portions and intervening marginal portions, a support adjacent to said form carrying cylinder, a plurality of inking surfaces on said support registering with the printing portions of the form, and means for dampening the printing and marginal portions of the form. 110

5. A printing machine comprising: a plurality of members constituting a printing couple, one of said members being a form carrying cylinder, a flexible form on said cylinder consisting of side by side plates having printing portions with intervening 120 marginal portions, a support adjacent to 125 said form carrying cylinder, a plurality of inking surfaces on said support registering with the printing portions of the plate, and means for dampening the printing and marginal portions of the plates. 130

6. A printing machine comprising: a plurality of members constituting a printing couple, one of said members being a form carrying cylinder, a plurality of flexible plates, means for removably securing said plates side by side on the form carrying cylinder, each plate having a printing portion and a marginal portion, a support adjacent to said form carrying cylinder, a plurality of inking surfaces on said support registering with the printing portions of the plates, and means for dampening the printing and marginal portions of the plates. 30

5

7. A printing machine comprising: a plurality of members constituting a printing couple, one of said members being a form carrying cylinder, a flexible form on said cylinder having side by side printing portions and intervening marginal portions, a support adjacent to said form carrying cylinder, a plurality of inking surfaces on said support registering with the printing portions of the form, and a full length dampening roller adapted to dampen the entire 40

10

20

25

planographic form. 45

8. A printing machine comprising: a plurality of members constituting a printing couple, one of said members being a form carrying cylinder, a flexible form on said

cylinder consisting of side by side plates 30 having printing portions with intervening marginal portions, a support adjacent to said form carrying cylinder, a plurality of inking surfaces on said support registering with the printing portions of the plates, and a 35 full length dampening roller adapted to dampen all the plates.

9. A printing machine comprising: a plurality of members constituting a printing couple, one of said members being a form carrying cylinder, a plurality of flexible plates, means for removably securing said plates side by side on the form carrying cylinder, each plate having a printing portion and a marginal portion, a support adjacent to said form carrying cylinder, a plurality of inking surfaces on said support registering with the printing portions of the plates, and a full length dampening roller adapted to dampen all the plates. 50

Signed at Plainfield, in the county of Union and State of New Jersey, this 18th day of November A. D. 1915.

WALTER CHARLES SCOTT.
